(57) **CLAIM**

The ornamental design for a fluid dispenser, as shown and described.

DESCRIPTION

FIG. 1 is a perspective view of a fluid dispenser showing our new design;

FIG. 2 is a left side elevational view thereof;

FIG. 3 is a front elevational view thereof;

FIG. 4 is a right side elevational view thereof;

FIG. 5 is a rear elevational view thereof;

FIG. 6 is a top plan view thereof;

FIG. 7 is an additional perspective view thereof;

FIG. 8 is an additional left side elevational view thereof;

FIG. 9 is an additional front elevational view thereof;

FIG. 10 is an additional right side elevational view thereof;

FIG. 11 is an additional rear elevational view thereof; and,

FIG. 12 is an additional top plan view thereof.

The broken-line disclosure in the views is understood to represent portions of the article in which the claimed design is embodied, but which form no part of the claimed design.
